(57) **CLAIM**

We claim the ornamental design for a stand for all-in-one computer, as shown and described.

DESCRIPTION

FIG. 1 is a perspective view of a stand for all-in-one computer showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view showing an illustration of use thereof.

The broken lines in the drawing figures are included for the purpose of illustrating environment and form no part of the claimed design.
